UNITED STATES PATENT OFFICE

135,300

DESIGN FOR AN EMBLEM PIN

Ben Felsenthal, New York, N. Y.

Application December 21, 1942, Serial No. 109,084

Term of patent 3½ years

To all whom it may concern:

Be it known that I, Ben Felsenthal, a citizen of the United States of America, residing in New York city, county of New York and State of New York, have invented a new, original, and ornamental Design for an Emblem Pin, of which the following is a specification, reference being had to the accompanying drawing, forming part thereof.

Fig. 1 is a plan view of an emblem pin showing my new design.

Fig. 2 is an edge view thereof.

The dominant feature of my design resides in the portion shown in solid lines.

I claim:

The ornamental design for an emblem pin, substantially as shown and described.

BEN FELSENTHAL.
